BOTTLE STOPPER

Claude H. Strickland, Edward D. Eberts, and Donald Lee Robb, Cincinnati, Ohio, assignors to Schenley Industries, Inc., New York, N. Y., a corporation of Delaware

Application October 28, 1953, Serial No. 388,786

10

1 Claim. (Cl. 215—7)

The present invention relates generally to containers, and is particularly directed to fluid containers and closures therefor.

As is well known to those versed in the art, it has been found economically impractical and otherwise undesirable to provide excessive empty space or head room in conventional containers which are used for volatile or expansible fluids, such as alcoholic beverages, etc. Consequently, serious difficulties have been experienced, as for example, the violent expulsion of bottle stoppers and the explosion of bottles when the same are subjected to relatively high temperatures. As such bottles may be filled and packed under one set of climatic conditions and transported to remote parts of the earth having very different climatic conditions, it has not been possible in the past to employ uniformly filled, like containers without the above mentioned undesirable results. Further, alcoholic beverage containers are frequently displayed in store windows and show cases under heavily lighted and poorly ventilated conditions, so that the bottle contents are heated and expanded, and therefore likely to cause explosions resulting in personal injury.

Another disadvantage encountered in the use of conventional containers is the necessity of breaking the paper or plastic seal which is usually wrapped around and secured to the bottle neck and adjacent portion of the closure or stopper. Such seals are commonly broken by manually running the knife or other sharp instrument about the bottle neck, a time consuming and dangerous procedure for unskilled hands. In the case of alcoholic beverages, an additional, Government tax stamp or seal is secured over the bottle stopper and along the bottle neck. Although Government seals serve to increase the difficulty encountered in opening bottles, as mentioned above, they are often inadvertently broken before sale and must be replaced.

Accordingly, it is a principal object of the present invention to provide an improved bottle closure or stopper which obviates the above mentioned disadvantages, by novel means permitting safe expansion of the contents of a bottle, without adding to the size of the bottle or detracting from its appearance.

It is another object of the present invention to provide a bottle stopper having the characteristics mentioned in the foregoing paragraph which is constructed to permit quick and easy severance for a bottle seal by a single manipulation; and which is provided with novel means to prevent the inadvertent breaking of the seal during handling or the like.

It is a more particular object of the present invention to provide a bottle stopper having a hollow shank and a hollow head, the latter defining a chamber communicable with the interior of a bottle to permit the expansion of fluid contained therewithin.

It is a further object of the present invention to provide a bottle stopper of the type described which is simple in construction and durable in operation, and which can be manufactured at a relatively low cost.

2

Other objects of the present invention will become apparent upon reading the following specification and referring to the accompanying drawings, which form a material part of this disclosure.

5 The invention accordingly consists in the features of construction, combinations of elements, and arrangements of parts, which will be exemplified in the construction hereinafter described, and of which the scope will be indicated by the appended claim.

In the drawings,

Figure 1 is a perspective view showing a bottle stopper constructed in accordance with the present invention; and

Fig. 2 is a sectional view taken substantially along the line 2—2 of Fig. 1.

Referring now more particularly to the drawings, the embodiment of the invention illustrated therein comprises a shank, generally designated 10, and an enlarged handle or head, generally designated 11, on one end of the shank.

15 The shank 10 includes a hollow open ended tubular member 12 having an external circumferential groove 13 adjacent to and spaced from the shank end 14.

The enlarged head 11 is fixedly secured to, or formed integrally with the end 15 of the tubular member 12, and has a hollow interior chamber 16 opening into the hollow of the tubular member. The head 11 is formed with a pair of laterally projecting hollow wings 17 and 18, and a recessed portion or groove 19 extending between the wings and over the head from one side thereof to the other. The head 11 is further formed with a circumferential bead 20, which defines an annular shoulder 21 facing toward the shank end 14.

25 The shank 10 also includes a yieldable, tubular cover 23, which is preferably fabricated of cork or other suitable material, and rotatably circumposed about the tube 12. The covering 23 is arranged with one end 24 in engagement with the shoulder 21 and the other end 25 adjacent to the annular groove 13.

30 An annular member or ring 26 is circumposed about the tube 12 adjacent to the end 14, and is formed with an internal shoulder 27 adapted to seat in the groove 13. The ring is arranged in engagement with the cover end 25 to prevent longitudinal displacement of the cover and removal of the latter. It is preferred to fabricate the ring 26 of polyethylene, or other suitable material having sufficient resiliency to permit engagement of the ring over the end 14 of the tube 12, and sufficient stiffness to prevent removal therefrom.

35 It will now be understood that the tube or cover 23 is rotatably mounted on the tube 12, and is positively retained on the latter by the ring 26. Further, the tube 12 communicates between the interior of the head 11 and the region exteriorly of the tube.

40 In operation, the head 11 serves as a handle for inserting the shank 10 into the neck of a bottle (not shown) and withdrawing the shank from the bottle neck. The tubular member 23 is engageable with the interior wall of a bottle neck for sealing the bottle opening, and serves to mount the head 11 and tube 12 for rotative movement with respect to the bottle. Further, the wings 17 and 18 permit the application of increased torque or leverage for readily effecting rotative movement of the head 11 with respect to the bottle.

45 It will now be apparent that the interior 16 of the head 11 defines a chamber which communicates through the tube 12 with the interior of a bottle when the shank 10 is inserted in the neck of the bottle. Hence, upon expansion of a fluid disposed within the bottle, the fluid is permitted to pass through the tube 12 and into the chamber 16, the latter serving to accommodate a substantial portion of the fluid and preventing the explosion of the bottle or expulsion of the stopper.

As a sheet of paper or plastic material is usually wrapped around and secured to the bottle neck and stopper, to seal the bottle, it will now be understood that such a seal may be simply and effectively severed by mere manual rotation of the head or handle 11. Further, as is conventional in alcoholic beverage containers, the tax stamp or seal is arranged over and secured to the bottle stopper and bottle neck. It will now be appreciated that the recessed portion 19 is admirably well adapted to receive such a tax stamp. That is, a tax stamp seated in and secured to the recessed portion 19 will be protected from inadvertent tearing or other breakage by the raised adjacent portions of the wings 17 and 18. Further, the portion of a tax stamp secured to the head 11 may be quickly and easily severed from the portion or portions secured to the bottle neck by simply turning the head, as described hereinabove.

From the foregoing, it is seen that the present invention fully accomplishes its intended objects, and provides a bottle stopper which is well adapted to meet practical conditions of manufacture and use.

Although the present invention has been described in some detail by way of illustration and example for purposes of clarity of understanding, it is understood that certain changes and modifications may be made within the spirit of the invention and scope of the appended claim.

What is claimed is:

A bottle stopper comprising a tubular shank having an open lower end and an open upper end, a hollow bulbous handle integral with the upper end and in fluid communication with the shank, said handle at the juncture with the shank forming an annular outstanding shoulder on the exterior of the upper end of the shank, a yieldable sleeve

member circumposed about the shank for positioning in the neck of a bottle and rotatable relative to the shank to permit rotation of the handle with respect to the bottle when the shank is inserted into and removed from the neck of a bottle, said shank having an annular seat formed exteriorly adjacent its lower end, an annular elastic member having a lip fixedly circumposed in the seat against displacement therefrom and bearing against the lower end of the yieldable member to locate it against axial movement, said handle having opposing hollow sides and a top to accommodate the expanding contents of a bottle into which it is inserted and having a central recessed portion extending across the top and down the sides, said recessed portion being disposed at the center of the handle above and in line with the shank to receive a seal extending from the sides of the recessed portion down along the outside of the neck of a bottle and adapted to be fixed thereto at opposite points, and said handle having bulged ends forming hand grips to afford increased leverage for manual rotation of the handle.
